D25-58.

OR D11,679

EX

No. 11,679

March 16, 1880

UNITED STATES PATENT OFFICE.

WILLIAM A. MESTAYER, OF PHILADELPHIA, PENNSYLVANIA.

DESIGN FOR A STAGE-SCENE.

SPECIFICATION forming part of Design No. 11,679, dated March 16, 1880.

Application filed January 14, 1880. Term of patent 3½ years.

To all whom it may concern:

Be it known that I, Wm. A. MESTAYER, of Philadelphia, Pennsylvania, have originated a Design for a Stage-Scene, of which the following is a clear, full, and exact description, reference being had to the accompanying photographic illustration, making part of this specification.

My design consists in a theatrical scene the center portion of which is a representation of the interior of a railway sleeping-car, as seen at *a* in the accompanying photographs. On each side of the representation of the car are appropriate landscapes, as proper surroundings, and in perspective, so as to represent a background. On the right of the representation of the car, at *b*, is shown a telegraph-

pole with wires and trees, with mountain scenery in the distance. To the left of the car, at *c*, are shown trees and a background, *20* also of mountain scenery.

What I claim as new, and desire to secure by Letters Patent, is—

The design for a stage-scene, consisting, essentially, of a central portion, *a*, formed in *25* representation of the interior of a sleeping-car, substantially as described, and shown in the accompanying photographic illustration.

WILLIAM A. MESTAYER.
